MACHINE FOR PACKING FIRECRACKERS

Raymond C. Hitt, Seattle, Wash.

Original application March 11, 1938, Serial No. 195,326. Divided and this application August 28, 1939, Serial No. 292,296

6 Claims.

(Cl. 86—20)

This invention relates to machines for packing firecrackers; and this application is a divisional one, from an original application filed by this applicant March 11, 1938, Serial Number 195,326 for making and packing firecrackers.

The objects of this invention are to provide a machine for binding a charge of powder centrally within a tube and for binding such tube upon a sheet of cardboard for display and use. A particular object is to bend and compress into the open ends of such tubes flexible tongues from opposite sides of such sheets for thereby retaining such charges of powder within such tubes, and for retaining said tubes on such sheets both by said tongues.

With these and other objects to be herein-after stated I have illustratively exemplified my invention by views and figures from drawings first filed in said original application and particularly described as follows:

Figure 1 is a side elevation of the machine for binding the tongues of the holding sheet into the ends of the container tubes, and also shows a carrier belt with several sheets of cardboard disposed upon the same and bunches of open ended tubes disposed upon several of said sheets.

Figure 2 is a plan view of the parts shown in Fig. 1, and showing one separate sheet of cardboard with tongues divided along opposite edges thereof and all flatly disposed upon the belt, and several other sheets with tubes positioned thereon.

Figure 3 is a cross section view of a portion of Fig. 1, taken on line 22, of Fig. 1.

Figure 4 is a sectional fragmentary detail of a portion of Fig. 1, taken on line 23, of Fig. 1.

Like characters on the different figures represent like parts. *h* represents open ended tubes into which charges of powder preferably in sacks with protruding fuses *e*, have been previously positioned centrally therein. *I* represents holders or packer sheets, preferably of thin cardboard material for mounting and sustaining such tubes in bunches thereon. *J* represents tongues divided by slits along opposite sides of the sheets adapted to be bent into the ends of the tubes for retaining the charges of powder therein and for retaining the bunches of tubes upon the sheets.

38" represents a rectangular frame preferably in elevated position as on legs 38". 74 represents a conveyer belt for moving the sheets, which is slidably mounted longitudinally over the frame. This belt at one end is rotatably mounted over sprocket 76, which is affixed to a stub shaft 77, on which is affixed an actuating gear 78. Said

gear may be turned together with said shaft 77, Fig. 1, by any other suitable source of power. Said belt is extended in loop form over said sprocket 76, and over a sprocket 83, at the 5 opposite end of the frame, which latter sprocket is affixed upon stubshaft 84".

Side rails 84 are provided for guides for the sheets *I*. Floor plates 85 are provided between the rails and are spaced apart by a flat bar 86, 10 which serves as a bed or bottom of a groove or channel between the side frames 38", for the belt 74. Said belt is provided with outstanding blades 75, suitably spaced for one or more of said sheets *I*, which latter lap over and beyond 15 the channel, and upon the plates 85. Brackets 87 are attached to the inner side of the rails 84, to keep the tubes upon the sheets centrally over the channel as they are moved along with the sheets; and are spaced above the plates to permit 20 the ends of the sheets to pass between.

The front end of these brackets is located at a suitable distance from the front end of the frame 38" to provide a space where the sheets *I* and tongues may be deposited upon the belt between 25 the blades 75. The rear end of the brackets terminate at a point where the slitted tongues of the sheets are to be upturned, as next explained. On each side of said channel and suitably spaced apart, are beveled edged members preferably 30 in form of perpendicular discs 88, for upturning the tongues as the sheets are carried along by belt 74. These discs are preferably mounted on a driving shaft as 89, and rotated clockwise to facilitate the upbending of the ends by sprocket 35 90, chain 91, and sprocket 92 on shaft 84. The bodies of the sheets are held down at this point by the firecracker tubes thereon, and a cover plate 93, suspended by a brace 94, over the tubes. Crimper wheels 95, with spaced teeth or fingers 40 96 thereon, are horizontally mounted on shafts 97, and 98, and thereby revolved in line with the centers of the tubes, and are suitably regulated so that as the upturned sections of the sheets pass opposite the fingers, such tongues 45 will be compressed by the fingers into the open ends of the respective tubes *h*, as they are carried along by said belt and blades thereon. The several firecrackers and sheets are thus combined into suitable packs and drop from the belt 50 into any suitable receptacle.

The perpendicular shafts for the crimper wheels, are driven by a bevel gear 99, affixed to the end of shaft 89. This drives gear 100 attached on a stub shaft 101, and the latter turns another gear 102, attached on the other end thereof,

whereby a gear 103 which is affixed to shaft 98, is turned and the crimper wheel 95, revolved. The oppositely positioned crimper wheel 95, is turned by a flat gear wheel 104, attached to the shaft 98, which meshes with a similar flat gear 105, affixed to lower end of said shaft 97.

Variations may be made in the mechanism and in method of connecting and driving the various parts, and I do not limit my invention to the specific construction shown in the drawings. It will be seen by reference to the drawings, that the above described chain 91, for turning shaft 89, is driven by sprocket 92, affixed on shaft 84', which latter is rotated by the sprocket 83 and the carrier belt or chain 74.

Having described my invention I claim as new:

1. A machine for assembling and attaching together a number of tubes with powder sacks therein in packs, comprising a rectangular frame, with a parallel channel along the top thereof, carrier wheels rotatably mounted at each end of the channel, an endless flexible belt movably positioned in the channel and over said wheels to be moved thereby through the channel, blades attached to and projecting above the belt and channel for conveying sheets with flexible tongues along and over said channel, floor plates on each side of the channel to support the sheets, guard rails on the outer edges of the plates, and brackets on the inner sides of the rails spaced above the plates, to permit the sheets to travel on the belt and to hold loaded firecracker tubes centrally on the sheets, with means for turning up the side edges of the sheets, a plate suspended above the tubes to prevent the sheets from rising when their edges are so upturned, and revolving wheels opposite the open ends of the tubes with fingers around the peripheries thereof for compressing sections of the upturned edges of the sheets into the ends of the tubes for binding sacks of powder in the tubes, and binding the tubes upon the flexible sheets, with means for moving all of said wheels simultaneously, with said belt.

2. A machine for packing firecracker units by attaching them to a sheet of material, with flexible tongues on the ends thereof, comprising a frame with means operated along the same for conveying the sheets of material and units to be attached, means along the line of travel of the sheets for upturning the flexible sections, and crimping means for forcing the upturned sections into the adjoining open ends of the firecracker units.

3. A machine for connecting firecracker units upon a sheet of flexible material, comprising a

rectangular channel, an endless belt operated along the channel for conveying the sheets, and units to be united, guards spaced along the channel for holding the sheets and units centrally over the belt, means for upturning the outer ends of the sheets, and crimping means for compressing such upturned ends into the open ends of the firecracker tubes.

4. A machine for attaching a plurality of firecracker units upon a sheet of material with flexible slotted edges, comprising a frame for supporting the sheets and the units centrally thereon, means for upturning the sections of the slotted edges opposite the ends of the firecracker units, means for crimping the upturned sections into the open ends of the units, with means for operating the upturning means and crimping means, each to act separately and simultaneously on each end of the respective units, and successively with each other.

5. A machine for attaching open ended articles to a sheet of thin material with flexible edges, comprising, a rectangular frame, a channel parallel along the top of the frame, an endless belt operatively mounted in the channel, carrier blades, attached to and extending from the belt for moving the sheets of material and articles along the frame, means for upturning the flexible edges opposite the open ends of the articles, wheels mounted horizontally on each side of the frame with projections around the periphery thereof for compressing sections of the flexible edges into the open ends of the articles as they are moved by the belt, with means for operating the belt and wheels simultaneously.

6. A machine for attaching firecrackers upon a sheet of material with flexible tongues on the edges thereof, comprising a conveyor belt horizontally and slidably positioned over a plate and within a channel, said belt adapted to carry said holding sheets for connecting said container tubes thereto, members disposed on opposite sides of said last named belt adapted to bend slotted tongues on the edges of such sheets upward and across each end of said container tubes, wheels horizontally and rotatably mounted adjacent said upturned tongues, fingers on the periphery of said wheels adapted to press such tongues into opposite ends of said container tubes for binding sacks of powder within the said containers and for binding such containers upon such sheets, together with means for operating said belt conveyors, and other movable parts of said machine.
